US00D682277S

(12) **United States Design Patent**
Tasselli et al.

(10) **Patent No.:** **US D682,277 S**
(b4) **Date of Patent:** **** May 14, 2013**

(54) **CODED INFORMATION READER**

(75) Inventors: **Corrado Tasselli**, Turin (IT); **Stefano Vassura**, Rastignano (IT); **Monica Alegiani**, Silvi (IT); **Manlio Galanti**, San Giovanni in Persiceto (IT)

(73) Assignee: **Datalogic IP Tech S.R.L.**, Lippo di Calderara di Reno (BO) (IT)

(**) Term: **14 Years**

(21) Appl. No.: **29/425,821**

(22) Filed: **Jun. 27, 2012**

(30) **Foreign Application Priority Data**

Dec. 30, 2011 (EM) 1970237

(51) **LOC (9) Cl.** **14-02**

(52) **U.S. Cl.**

USPC **D14/428; D14/426**

(58) **Field of Classification Search** D14/420, D14/426–430, 453, 346, 341, 347, 412; D13/107, D13/184; 358/473; 235/462.43, 462.45, 462.47, 235/462.48, 462.44, 462.46, 487, 472.01, 235/472.02; 16/110.1, 430, 431; 439/133, 439/135; 709/219, 201; 710/73; 320/114, 320/115, 123; 361/679; 382/313, 321; 455/575.1, 455/561, 572

See application file for complete search history.

(57) **CLAIM**

We claim the ornamental design for a coded information reader, as shown and described:

DESCRIPTION

FIG. 1 is a perspective front view of a coded information reader according to the present invention.

FIG. 2 is a perspective rear view of the coded information reader of FIG. 1.

FIG. 3 is a front view of the coded information reader of FIG. 1.

FIG. 4 is a rear view of the coded information reader of FIG. 1.

FIG. 5 is a right side view of the coded information reader of FIG. 1.

FIG. 6 is a left side view of the coded information reader of FIG. 1.

FIG. 7 is a top view of the coded information reader of FIG. 1; and,

FIG. 8 is a bottom view of the coded information reader of FIG. 1.

Broken lines and unshaded portions contained within broken lines are not claimed.

1 Claim, 8 Drawing Sheets
